UNITED STATES PATENT OFFICE.

ANTON CHRISTENSEN, OF CHICAGO, ILLINOIS.

CAR-BRAKE.

SPECIFICATION forming part of Letters Patent No. 732,516, dated June 30, 1903.

Application filed April 22, 1903. Serial No. 153,763. (No model.)

To all whom it may concern:

Be it known that I, ANTON CHRISTENSEN, a citizen of the United States, residing at Chicago, in the county of Cook and State of Illinois, have invented certain new and useful

Improvements in Car-Brakes; and I do hereby declare the following to be a full, clear, and exact description of the invention, such as will enable others skilled in the art to which it applies to make and use the same, reference being had to the accompanying drawings, and to the letters and figures of reference marked thereon, which form a part of this specification.

15 This invention relates to that class of car-brakes in which the brakes are actuated by the momentum of the car and comprises particularly a rail-brake operated by a clutch and drum on the axle.

20 The object of the invention is to form an improved apparatus of the kind stated, as will more fully appear in the following description and claims.

In the accompanying drawings, Figure 1 is 25 a plan view of the apparatus, a portion only of the car-frame being shown. Fig. 2 is a side elevation, partly in section. Fig. 3 is a cross-section. Fig. 4 is a detail in section of the clutch and drum, and Fig. 5 is a perspective view of the adjustable sectional brake-shoe used in the apparatus.

Referring specifically to the drawings, 30 indicates portions of the car-frame; B, the wheels; A, the axle; E, a winding-drum joined to a frusto-conical head C', which cooperates with a flange-collar C to produce a friction-clutch to rotate the drum. The drum and head are rotatable and longitudinally slideable on the axle, as will be understood.

40 D is a collar which fits loosely over the neck of the clutch-head and is pivotally joined to one arm of a bell-crank d, pivoted to vibrate horizontally on a bracket d⁸, attached to the car-frame. The other arm of the bell-crank 45 is connected by link d' to a vertically-acting bell-crank formed by a rock-shaft d³, supported in suitable brackets attached to the car-frame and arms d² and d⁹ thereon. The arm d⁹ is connected by rod d⁴ to an operating-lever d⁵, which extends through the floor 50 of the car in suitable position to be operated by the driver.

The clutch may be operated from the other end of the car by means of a lever d⁶, similar to the lever d⁵, connected by a long rod d⁷ to the link d' and the bell-crank.

55 It will be seen that appropriate movement of either lever will throw the clutch in engagement and rotate the drum to wind up the cable F attached thereto and operate the 60 brake.

At each side of the car-frame, above the rails, is a guide-housing H', in which the brake-shoes H slide vertically to bear upon the rails. This action is produced by a system of levers connected to the cable F, comprising particularly a horizontal rock-shaft f', having an arm f, to which the cable is attached, and arms g³, connected by links g, g', and g² to levers G, which are fulcrumed 70 to vibrate vertically in brackets g⁴, supported on the housings H'. These levers G are connected by links h² to short levers h, which are fulcrumed at h⁴ on top of the housings and connected by links h' to lugs projecting from 75 the top of the brake-shoes. The links h' are so disposed that they may and will follow the shoe H down into the housing when the brakes are set.

80 Each of the brake-shoes, as shown in Fig. 5, consists of an upper portion 7 and a lower portion 8, connected by bolts 9, whereby they may be spaced apart as desired to take up wear and adjust the shoes to the distance of the car-body from the track. The parts of 85 the shoe have at each edge flanges a, which slide in appropriate guide-grooves in the housing. The brake-shoes are normally held up by springs G', connected to the levers G and a fixture on the housing. The housings 90 are spaced and supported by braces h⁵, extending across between the same.

What I claim as new, and desire to secure by Letters Patent, is—

1. The combination with a car, of an axle-clutch and winding-drum, hand-operated connections for throwing the clutch, vertically-slideable rail brake-shoes, and connections between the drum and the shoes including vertically-acting levers over the shoes and connected thereto.

2. The combination with a car, a clutch slideable lengthwise on the axle thereof, a winding-drum operated by the clutch, rail-

engaging brake-shoes, and connections between the drum and the shoes, of an operating-lever extending through the car-floor, and connections between the lever and the clutch 5 including connected horizontally and vertically acting bell-cranks.

3. The combination with a car, rail-engaging brake-shoes thereon, a clutch member and drum 10 slidable lengthwise on the car-axle, and connections between the drum and the shoes, of a collar on the clutch member, a bell-crank pivotally supported on the car and connected to the collar to shift the clutch member, and means to operate the bell-crank.

15 4. The combination with a car, a housing thereon having vertical guides, of a brake-

shoe slidable in the guides and having two parts adjustably spaced.

5. The combination with a car, and a clutch-drum on the axle thereof, of a rock-shaft extending crosswise of the car and connected to the drum, vertically-slidable rail brake-shoes, vertically-swinging levers above the shoes and connected thereto, and connections between the rock-shaft and levers. 20 25

In testimony whereof I affix my signature in presence of two witnesses.

ANTON CHRISTENSEN.
